UNITED STATES PATENT OFFICE.

SAMUEL TAYLOR BEARE, OF JACKSON, TENNESSEE.

REFRIGERATOR.

Application filed November 14, 1927. Serial No. 233,216.

This invention relates to improvements in refrigerators,—one object of the invention being to provide a simple and efficient structure in which a combined freezing and cooling unit is built into the upper portion of the casing of a refrigerator box, preferably of the "top icer" type, and to provide simple baffle devices which shall be so arranged as to compel an efficient circulation of air about 10 said combined freezing and cooling unit and through the chambers of the refrigerator.

With this and other objects in view, the invention consists in certain novel features of construction and combinations of parts 15 as hereinafter set forth and pointed out in the claims.

In the accompanying drawings,—

Figure 1 is a view in front elevation.

Figure 2 is a front view (with the front 20 removed) illustrating an embodiment of my invention.

Figure 3 is a transverse sectional view of the freezing and cooling unit, and

Figure 4 is a view partly in side elevation 25 and partly in section illustrating the position of the freezing and cooling unit and the drip and drain means therefor.

The box or casing of a refrigerator of the top icer type is shown at 1 and the walls of 30 the same may include cork board or other type of insulation. The top of the box or casing is provided with an opening 2 normally closed by a top icer door 3, to facilitate the introduction of ice into a freezing 35 and cooling unit 4. This unit comprises a tank made of sheet metal or other suitable material and may be built into the upper portion of the refrigerator box or casing. An insulated baffle 5 preferably of cork board 40 is located at one end of the unit 4 and spaced from one side wall of the box or casing to form a passageway 6. A passageway 7 is also located between the opposite end of the unit 4 and the adjacent side wall of the box 45 or casing. Extending downwardly from the central portion of the unit 4 is a baffle 8 preferably of cork board or other insulating material and between the upper end of said baffle 8 and the baffle 5, an insulated member 50 9 (preferably of cork board) is located and constitutes a shelf upon which a portion of the unit 4 is located. The baffle 8 terminates short of the bottom of the box or casing 1 to form a passage 10 which connects the chambers 11 and 12 of the refrigerator. Flanges

13 extend upwardly and somewhat laterally from the unit 4 at respective sides thereof and terminate at their upper ends against the top of the box or casing at or near respective sides of the opening 2. Each of the side 60 flanges 13 is provided with a slot or opening 14 constituting vents between the passages 6 and 7 and a passage 15 over the unit 4. With the arrangement above described, an efficient circulation of air will be provided about the 65 freezing and cooling unit and such air, chilled by its passage about said unit will be compelled to circulate through the chambers 11 and 12 of the refrigerator box or casing.

The freezing and cooling unit 4 is adapted 70 for the reception of a refrigerating element. In the present instance, several compartments 16, 16, 17 and 18 are located within the unit 4. The compartments 16 and 17 communicate with openings 18'—19 in the 75 front wall of the unit and the front ends of the compartments 16 and 17 are secured by solder or otherwise to the front wall of the unit. The rear edges of the compartment 18 may be soldered or otherwise secured to the 80 rear wall of the unit, and is adapted to receive ice 20, either in the form of a block or in crushed condition. In the space surrounding the compartments in the unit 4, crushed ice and salt may be located as indicated at 21 and this mixture as well as the ice indicated at 20 may be inserted through the opening 2. The compartments 16 and 17 receive drawers or trays 22—23 to contain material to be chilled or frozen. 85

A drip and overflow pipe 24 communicates with the chamber or compartment 18 and a pipe 25 communicates with the bottom portion of the tank of the unit, both of said pipes discharging into a funnel 26 at the 90 upper end of a drain pipe 27.

A single door 28 closes food chambers of the refrigerator and a smaller door 29 is located in front of the freezing and cooling unit to permit ready access to the latter. 100

Having fully described my invention what I claim as new and desire to secure by Letters-Patent, is:

1. The combination with a refrigerator box or casing, of a freezing and cooling unit built into the upper portion thereof and spaced from the side walls and top of said box or casing, an insulating baffle extending downwardly from said unit between the ends thereof and terminating at its lower end 105

above the bottom of the box or casing, an insulating member covering one end of said unit and spaced from the adjacent side of the box or casing, and an insulating member under said unit and extending between the first mentioned insulating member and said baffle.

2. The combination with a box or casing of a refrigerator, of a freezing and cooling unit located in the upper portion of the box or casing and spaced from the side walls and top thereof whereby passages are formed at the sides of the unit and over the top thereof, said passages communicating at their lower ends with chambers in the refrigerator box or casing, a baffle separating said chambers except at their lower ends, and flanges at the sides of said unit and extending to the top of the box or casing, said flanges having openings therethrough whereby the passages at the sides of said unit communicate with the passage over said unit.

3. The combination with a box or casing of a refrigerator having an opening in its top and closure for said opening, of a freezing and cooling unit located in the upper

portion of said box or casing, said unit having openings in its front side, a plurality of compartments located within said unit and communicating with the respective openings in the front side thereof, the unit having an ice chamber in its rear side and being open at its top to receive brine material to surround said several compartments and the front and ends of the ice chamber, and drawers or trays to enter said compartments.

4. The combination with a box or casing of a refrigerator having an opening in its top and a closure for said opening, of a freezing and cooling unit open at its top, an ice compartment located within said unit, other compartments located within said unit and accessible from the front thereof, said unit adapted to contain refrigerant material to surround said last mentioned compartments and engage walls of the ice compartment, and means whereby material to be chilled or frozen may be introduced into said other compartments.

In testimony whereof, I have signed this specification.

SAMUEL TAYLOR BEARE.
